ISADORE ROSENBERG, OF PORT CHESTER, NEW YORK.

FOLDING VALVE-LIFTER.

1,302,975.

Specification of Letters Patent. Patented May 6, 1919.

Application filed June 3, 1918. Serial No. 237,937.

To all whom it may concern:

Be it known that I, ISADORE ROSENBERG, a citizen of the United States, residing at Port Chester, county of Westchester, State 5 of New York, have invented an Improvement in Folding Valve-Lifters, of which the following is a specification.

This invention has for its object to provide a simple, inexpensive, compact, easily 10 operated and thoroughly reliable folding tool for compressing valve springs in hydro-carbon engines to permit removal of the valves, the common trade name for this class of tools being valve lifters.

With these and other objects in view, I have devised the novel folding spring compressing tool which I will now describe referring to the accompanying drawing forming a part of this specification and using 20 reference characters to indicate the several parts.

Figure 1 is an elevation of my novel valve lifter, folded as when not in use;

Fig. 2 an elevation on a reduced scale 25 illustrating the use of the tool in compressing a valve spring to permit removal of the valve, and

Fig. 3 is a perspective view, partly in section, on the same scale as Fig. 1, showing 30 the tool set up ready for use, and illustrating its construction.

10 denotes a portion of the cylinder, 11 a portion of the valve chamber, 12 a portion of the combustion chamber, 13 the valve, 14 35 the valve stem, 15 the spring, 16 the spring seat and 17 the key by which the spring seat is held in place on the valve stem. These parts are in common use and may be of any ordinary or preferred construction.

18 denotes the body of my novel valve lifter, 19 a slide adapted to reciprocate therein, 20 the upper folding arm and 21 the lower folding arm. The upper folding 40 arm is provided with a detachable stud 22 having a point 23 which is adapted to engage the center of a valve, as in Fig. 2.

The end of the arm is enlarged and the stud is provided with a reduced shank having 45 a threaded engagement with a hole 41 in the

enlarged end of the arm. The slide is provided with an angle arm 24 and folding arm 20 is pivoted in a socket 25 in the end of the angle arm, the rear wall of the socket serving as a stop to limit the outward movement of the folding arm. Angle arm 24 is provided with a threaded hole 42 near its outer end which is engaged by the shank of stud 22, in the folded position of the tool as in Fig. 1, and acts to retain the 55 parts folded. The lower folding arm is provided at its outer end with a U-shaped head 26 which is adapted to engage the valve stem, as in Fig. 2. The inner end of this folding arm is provided with an 60 angle piece 27 which is pivoted in a slot 28 in the lower end of the body. The back face of the angle piece is adapted to engage the wall of the body to limit the outward movement of the arm. The rear face of the 65 slide is provided with a rack 29 which is engaged by a pinion 30 on a stud 31 pivoted in a housing 32 which is formed integral with or secured to the body. 33 denotes a lever branched at its inner end to straddle the housing, the branches being pivoted on stud 31, the ends of which extend beyond the housing on each side. Socketed in the 70 lever is a sliding dog 34 which is held in engagement with the pinion by a spring 35. 75 The dog has a straight face on one side and a beveled face on the other side, and has a shank 36 which extends longitudinally through the lever and is provided with a knurled finger piece for convenience in operation. The shank may have both longitudinal and rotary movement in the lever, so that when the dog is withdrawn out of engagement with the pinion, the shank and dog may be given a half turn in either direction 80 so as to change the engagement of the straight face of the dog from one tooth of the pinion to the contiguous face of the next tooth and thus reverse the movement of the pinion, and of the slide through engagement of the pinion with the rack, when the lever is oscillated.

85 37 denotes a block formed integral with or rigidly secured to the housing. Socketed in the block, is a dog 38 having on one side 90 95 engagement of the pinion with the rack, when the lever is oscillated.

95 37 denotes a block formed integral with or rigidly secured to the housing. Socketed in the block, is a dog 38 having on one side 100

a beveled face, and on the other side a straight face adapted to engage the teeth of the rack to lock the rack against movement in one direction. The dog has a shank 39 extending through the block and having a knurled finger piece for convenience in operation, and is normally held in engagement with the rack by a spring 40. This shank also has both longitudinal and rotary movement so that when the dog is withdrawn out of engagement with the rack, the shank and dog may be given a half turn in either direction so as to change the engagement of the straight face of the dog from one tooth of the rack to the contiguous face of the next tooth, and thus reverse the locking action of the dog on the rack. In order to prevent rotation of dog 38, except when it is withdrawn from engagement with the teeth of the rack, I provide a cross pin 43 in shank 39 which engages a slot 44 in block 37 while the dog is held in operative position by the spring, the pin being withdrawn from the slot when it is required to reverse the dog.

The operation will be readily understood from Figs. 2 and 3. In Fig. 3 the dogs are set to move the slide and stud downward relatively to the body when the lever is oscillated. The straight face of dog 34 faces upward, consequently upward swing of the lever will cause movement of the pinion counter-clockwise which will move the slide downward. When the lever is swung downward, dog 34 will slide over the teeth of the pinion. As the beveled face of dog 38 faces upward, the teeth of the rack will slide over it when the rack is moved downward, upward movement of the rack being prevented by the engagement of the straight face of dog 38 with the upper face of a rack tooth. Before placing the tool in use to compress a valve spring, point 23 and head 26 must be separated far enough, by operation of the lever, to permit the point to be placed in engagement with the center of the valve and the branches of the head to be placed on opposite sides of the valve stem below the key. When moving the slide upward both of the dogs must be reversed from the position shown in Fig. 3, that is the straight face of dog 34 must face downward and the straight face of dog 38 must face upward. When the dogs are in this position, downward swing of the lever will rotate the pinion clockwise and through the engagement of the pinion with the rack will move the slide upward relatively to the body. Suppose now that the dogs are in the position shown in Fig. 3 and that the tool has been placed in operative position, that is with the point engaging the valve and the head in engagement with the valve stem

below the key, upward swing of the lever 65 will cause the slide to move downward relatively to the body, the point and the head approaching each other, as in Fig. 2. The operator may now remove the key from the valve stem. The dogs are then reversed 70 and the slide is moved upward relatively to the body until the spring has expanded. The tool is then removed, the spring will drop off from the stem and the valve and stem may be lifted upward and removed. 75

Having thus described my invention, I claim:

1. A tool of the character described comprising a body, a U-shaped head carried thereby and adapted to engage a valve stem, 30 a slide having a rack, a point carried by the slide and adapted to engage a valve, a pinion carried by the body and engaging the rack, a lever pivoted to the body, a reversible dog socketed in the lever and adapted to actuate 35 the pinion in either direction to move the head and point toward or from each other, and means for preventing movement of the slide except by actuation of the pinion.

2. A tool of the character described comprising a body, a U-shaped head carried thereby and adapted to engage a valve stem, a slide having a rack, a point carried by the slide and adapted to engage a valve, a pinion carried by the body and engaging the 95 rack, a lever pivoted to the body, a reversible dog socketed in the lever and adapted to actuate the pinion in either direction, and a reversible dog engaging the rack and preventing movement of the slide except by 100 actuation of the pinion.

3. A tool of the character described comprising a body, a slide adapted to pass within the body and having an angle arm, a folding arm pivoted to the body and provided with a U-shaped head, an arm pivoted to the angle arm and adapted to fold over the first mentioned arm, and a stud having a valve engaging point and having threaded engagement with the last mentioned folding arm, said stud also having threaded engagement with the angle arm and acting to retain the arms in the folded position when not in use.

4. A folding tool of the character described comprising a body, a folding arm pivoted thereto and carrying a U-shaped head adapted to engage a valve stem, a slide adapted to pass within the body, and having an angle arm, a folding arm pivoted to the angle arm, and a stud having a valve engaging point and having threaded engagement with the last mentioned folding arm when in use, said stud also having threaded engagement with the angle arm to retain the arms in the folded position when not in use.

5. A tool of the character described com-

prising a tubular body, a slide adapted to pass within the body, folding arms pivoted to the body and to the slide respectively, a U-shaped head and a valve engaging point carried by the body and the slide respectively, a rack, pinion and lever, a reversible

dog in the lever which engages the pinion, and a reversible dog engaging the rack to prevent movement thereof except by actuation of the pinion.

10

In testimony whereof I affix my signature.
